(57) **CLAIM**

What we claim is the ornamental design of a connector for data transmission optic fiber, as shown and described.

DESCRIPTION

FIG. 1 is a perspective view of a connector for data transmission optic fiber showing our new design;

FIG. 2 is a front view thereof, the rear view being a mirror image thereto;

FIG. 3 is a left side view thereof;

FIG. 4 is a right side view thereof;

FIG. 5 is a top view thereof; and,

FIG. 6 is a bottom view thereof.

The broken line portion of the figure drawings is included to show unclaimed subject matter only and forms no part of the claimed design.

This application is based upon and claims the benefit of priority under 35 U.S.C. §119 from the prior Chinese Patent Application No. 201030705978.0, filed, Dec. 31, 2010, the entire contents of which are incorporated herein by reference in its entirety.
